SOAP FEEDER

Otto C. Schlack, Chicago, Ill.

Application July 22, 1938, Serial No. 220,740

9 Claims. (Cl. 221—96)

The present invention relates to a dispensing or feeding device and more particularly to a structure adapted for feeding powdered material at predetermined times.

5 The present invention contemplates more specifically the provision of a device for feeding a reagent, such as soap, in the powdered or particulate form and in delivering the powdered material to its point of use, the feeding and delivery being carried out through the agency of a flow of liquid.

10 It is an object of the present invention to provide a feeding and dispensing device, as above, adapted to handle and supply powdered material and to deliver it to a predetermined point of delivery in predetermined quantities, free from caking and clogging.

15 A further object of the present invention is to provide a soap feeding device, as above, which may be actuated under the influence of the flow of water or other liquid with which the powdered material is subsequently to be mixed but wherein the rate of feeding of the powdered substance is accurately controllable irrespective of 20 the flow or the quantity of said liquid flow. To this end the invention particularly comprehends the provision of a chamber or other water accumulating device actuated by the aforesaid flow of water to feed predetermined increments of 25 soap powder or the like but wherein the water actuated or accumulating member is provided with feed means for permitting ingress of the water at a predetermined, controlled rate.

30 The invention, therefore, further comprehends the provision of a feeding device, as above, having an adjustable control valve in combination with means to feed a flow of water in the vicinity of said control valve at all times.

35 An additional object of the present invention is to provide a powder agitating means actuated by the measuring and feeding means so that an accurately predetermined quantity of powder will be measured and delivered.

40 Numerous other objects and advantages will 45 more fully appear during the course and progress of the following specification.

Figure 1 is a perspective view of a portion of a washing machine embodying my present invention.

50 Figure 2 is a sectional view taken on the line 2—2 in Figure 1, portions of the device being broken away to show the exterior powder feeding structure.

55 Figure 3 is a sectional detail view taken on the line 3—3 in Figure 2.

Figure 4 is a sectional view taken vertically and centrally through the device shown in Figure 1.

Figure 5 is a sectional view taken on the line 5—5 in Figure 4.

Figure 6 is a view the same as Figure 5, but showing the relative position of the parts when actuated to dispense a quantity of powder.

Referring to the figures of the drawings, where-in the present invention is shown more in detail, Figure 1 illustrates one form of dispensing 10 device constructed in accordance with the present invention.

Attention is directed to the fact that the embodiment of the figures is disclosed as applied to a dishwashing machine, indicated more or less diagrammatically by the reference numeral 10 having side walls 12 and a top wall 14. The side walls support the plurality of trays 16 in which are situated the articles to be washed, while a spray head 18 supplies a continuous spray 20 of washing liquid for carrying out the washing step. It will be understood that the washing liquid may be circulated or recirculated in any desired manner although the details of the structure have not been disclosed for the reason that 25 per se they form no part of the present invention.

The dispensing or feeding device proper comprises an integral casting 20 mounted exteriorly of the washing device and secured to the wall 12 by means of a bracket 22. This casting 20 comprises an upper cylindrical container or hopper 24 open at the top for accommodating a quantity of reagent to be fed to the washing machine. For purposes of illustration it will be assumed that the hopper 24 contains a body of soap or 35 detergent powder. The lower portion of the casting 20 comprises a transversely extending cylinder 26 communicating at its top with the interior of the hopper 24 through the agency of an aperture 28. A diametrically opposed aperture 40 30 at the bottom of the cylindrical portion 26 is surrounded by a converging, generally conically arranged side wall 32 having the general configuration of a spout. This spout is adapted to deliver measured quantities of powdered material, as will hereinafter appear more in detail.

45 A measuring and feeding cylinder 34 is mounted within the outer cylinder 26, as shown in Figures 4 to 6, being so arranged therein as to fit securely while at the same time permitting rotation within the outer cylinder 26 about the common axis of the two cylinders. The central feeding cylinder 34 is rigidly mounted on the shaft 36 through the agency of set screws 38 so that actuation of the shaft in a manner to be 50 55

hereinafter described will control the rotational movement of the cylinder 34.

A recess 40 is formed in said last named cylinder by removing a portion of the material bounded by a flat plane intersecting the periphery of the cylinder 34 along spaced, parallel lines. Attention is directed to the fact that the recess 40 is aligned with the apertures 28 and 30 and, in normal position, is arranged as in Figure 5 directly under and in communication with the first named said aperture. In this position, therefore, the predetermined space provided by the recess 40 will normally tend to fill with material from the hopper 24 and, when rotated through about 90 degrees, will dispense this predetermined quantity of material through the aperture 30.

The central measuring cylinder 34 is retained in position within its enclosing tubular cylinder 26 by means of end caps 42 apertured centrally to permit passage of the shaft 36 and fastened rigidly to the casting 20 by machine screws 44. The shaft 36 and, accordingly, the associated parts are normally at rest, retained in the position shown in Figures 1 and 5 through the agency of a counter-weight 46 mounted upon the radially projecting arm 48 which is rigidly secured to the shaft 36 through the agency of a bushing 50 on the end of the arm having a pin 52 extending therethrough and through the shaft 36.

In accordance with the present invention it is contemplated that the counter-weight 46 comprise a tubular member retained on the arm 48 by means of collars 54 threadedly engaged therewith. It will thus be apparent that the counter-weight may be adjustably positioned along the arm for the purpose of controlling the counter-weight effect.

In order to assure the supply of constant and predetermined quantities of powder, the hopper 24 is provided with an agitating device 56 comprising U-shaped wire members 58 and 59 rigidly secured at their ends to a sleeve 60 fastened to the central shaft 62 through the agency of a set screw 63. The shaft 62 is rotatably journaled in opposed embossments 64 on the casting 20 in such a position that the agitator cage 56 resides just above the aperture 28 in the bottom of the hopper (see Figures 4 to 6 inclusive).

The agitator shaft 62 has an end portion 66 configurated in the form of a crank and engaging the bifurcated end 68 of an actuating lever 70 which is welded to the sleeve or bushing 50 as at 72. In other words, the engagement between the end 66 of the shaft 62 and the bifurcated end of the lever 70 provides a lost motion connection so that, when the shaft 36 is rotated, the shaft 62, and the agitator secured thereto, is rotated at a slightly greater angular speed for keeping the aperture clear of any coherent masses of powder.

Attention is particularly directed to the fact that the elongated members 58 and 59 of the agitator are positioned relatively closely together (Figures 5 and 6) and these members are so arranged that they sweep across the aperture 28 just as the recess 40 comes into alignment therewith. The other elongated members 58 normally operate relatively remotely from the aperture 28 and, accordingly, are relatively spaced apart.

The angular movement of the shaft 36 is limited through the agency of flanges 74 formed by bending over opposite side portions of the lever 70 and, as is clearly shown in the drawings, these bent-over portions or tabs extend in a direction normal to the lever 70 in a position to

strike against the adjacent embossment 64. Figures 5 and 6 specifically illustrate the position of the shaft 36 and its associated parts in either of its two limiting positions, as determined by contact of the flanges 74 and the embossment 64.

The present feeding device is actuated through the agency of a liquid accumulating device or tank 76 (Figures 1 and 2) welded to a supporting block or bushing 77 which is rigidly secured to the shaft 36 by means not shown. It should be noted that the tank or container 76 is so arranged that its center of gravity is horizontally offset from the axis of the shaft 36 and is provided with bottom and side walls, as well as an enclosing top wall 78.

The side walls are extended upwardly above the top wall 78 as at 80 so as to retain a quantity of liquid upon the top wall 78 at all times when in use. In other words, the side walls 80 provide a shallow receptacle for liquid sprayed thereinto. The liquid thus retained enters interiorly of the vessel 76 through the valve or control gate 82. As shown more clearly in Figure 3, the control aperture 82 comprises a cylindrical threaded bushing 84 mounted in the top wall 78 of the liquid accumulating tank 76, the bushing centrally accommodating a machine bolt 86 threaded therewith having an L-shaped central bore 88.

It will be seen, therefore, that liquid on the upper wall 78 will pass through the L-shaped bore 88 and this flow of liquid may be throttled by threading the machine screw axially into the bushing 84 in order to decrease the effective opening of the upper end of the L-shaped bore 88. Attention is particularly directed to the fact that the vessel 76 is provided with an aperture 90 in a short, upstanding side wall at the righthand side of Figure 2, which aperture permits emptying of the vessel 76 when in inverted position and vents the air in the tank at times when liquid is flowing inwardly through the throttle control valve 82.

From the foregoing, it will be apparent that, in normal operation, the upper surface of the tilting vessel 76 is so arranged that it is in the path of a portion at least of the spray directed by the spray heads 18. Accordingly, the tray provided by the upstanding edges 80 will continuously accumulate liquid which will pass through the bore 88 in the control valve 82.

When the vessel has been filled to a predetermined degree, it overbalances the counter-weight 46, causing the shaft to move in the direction of the dotted line arrow in Figure 2 until the tilting vessel reaches a lowermost position indicated by the dotted lines. In the construction shown, the shaft thus will have been moved through an angle in the neighborhood of 90 degrees to bring the dispensing cylinder 34 from the position shown in Figure 5 to the position shown in Figure 6.

In the last named position the measured quantity of powder in the recess 40 is permitted to drop through the aperture 30 in the spout 32 and thence through a suitable tube 94 connected therewith and leading into the lower part of the washing machine, as shown in Figure 1. The liquid contents of the vessel 76 meanwhile flow freely through the aperture 90, being vented by the valve control 82 and, when the tank ultimately becomes empty, the counter-weight 46 serves to return the parts to their original position at which time the tank again commences to fill with liquid from the spray head 18.

The present invention provides a dispensing device which is not dependent entirely upon the

flow of water from the spray head or heads 18 since adjustment of the control valve 82 will serve to determine the rate at which the tank 16 fills with liquid and, accordingly, the rate at which the powdered material is fed to the machine. 5 In other words, the rate of periodicity of actuation of the shaft 36 may be dependent on the setting of the member 82, a trap 96 being provided in the top of the washing machine for access thereto.

10 The present invention provides a highly simplified, efficient and inexpensive device for feeding material and particularly powdered material. In accordance with the present invention the powdered material is fed through the agency of a tiltable liquid accumulating device while being positioned relatively remotely from the flow of water. Thus, accurately predetermined amounts of liquid are added to the flow of powder so that 15 the concentration of powdered reagent in the water is fixed and remains constant in spite of the addition of fresh liquid or the utilization of the reagent from the liquid.

20 Changes may be made in the form, construction and arrangement of the several parts without departing from the spirit or scope of the invention, or sacrificing any of its attendant advantages, the form herein described being a preferred embodiment for the purpose of illustrating the 25 invention.

30 The invention is hereby claimed as follows:

1. In combination with a liquid flow device, means to feed a reagent to said liquid flow device comprising a hopper for said reagent, means to measure and convey a predetermined quantity of said reagent to a predetermined point, said measuring means being in closed communication with the hopper for receiving a predetermined quantity of said reagent and for preventing further feed thereafter, a tiltable liquid accumulating chamber operatively connected to said measuring means and arranged in the path of said liquid flow for tilting to actuate said means when a predetermined quantity of said flow has been accumulated, and valve control inlet means 40 on said accumulating chamber to control the ingress of liquid thereto and adjustable independently of the liquid flow to determine the periodicity of operation of said chamber.

45 2. In a proportional feed device of the class 50 described, a liquid flow device, a hopper for a powdered reagent exteriorly of the fluid flow device and having means thereon for receiving a predetermined quantity of reagent and delivering said predetermined quantity of reagent to the 55 interior of said fluid flow device, liquid accumulating means within the fluid flow device and adapted to be actuated when a predetermined quantity of liquid has been accumulated by the flow of liquid therein for periodically actuating said feeding means, and orifice means on the liquid accumulating means for restricting flow to said accumulating means irrespective of said flow in said fluid flow device for controlling the 60 frequency of operation of said device.

65 3. In a proportional feed device of the class 70 described for feeding powdered material to a flow of liquid, a feed hopper for powdered material, a cylindrical chamber beneath said hopper having therein a feeding cylinder, a recess in said feeding cylinder, means to rotate said feeding cylinder to a position wherein the recess is fed with powdered material from the hopper or to discharge position, agitating means within the 75 hopper and operatively connected with said rotat-

ing means to prevent cohering of the reagent during said feeding step, a liquid tilting chamber operatively connected to the cylinder for rotation of the cylinder to discharging position, said tilting chamber being adapted to be arranged in the path of said flow for actuation after a predetermined quantity of said flow is accumulated in the chamber.

5 4. In a device of the class described, means for feeding a predetermined quantity of powdered reagent to a predetermined point, means to actuate said feeding means comprising a tiltingly mounted, fluid accumulating vessel adapted to be placed adjacent a point in the fluid flow to receive a portion at least of said flow, and adjustable valve inlet means operatively associated with said vessel and restricting the admission of fluid to said tilting vessel whereby to control the rate of admission of fluid.

10 5. In a feeding device of the class described for feeding powdered material to a flow of liquid at a predetermined relative rate and having means for recurrently feeding a measured quantity of powdered reagent to a predetermined point, and means for actuating said feeding means; the improvement wherein said actuating means comprises a tiltably mounted, fluid accumulating vessel adapted to be arranged adjacent a path of fluid flow for receiving a portion at least of said flow, said vessel providing an interior chamber, an 15 upper portion above the chamber adapted to receive a limited quantity of fluid, and adjustable inlet control means between the said upper portion and said chamber for controlledly supplying fluid to the interior of said vessel, said vessel being 20 adapted to tilt when a predetermined quantity of fluid has been admitted thereto.

25 6. In a feeding device of the class described for feeding powdered material to a flow of liquid at a predetermined relative rate and having 30 means for recurrently feeding a measured quantity of powdered reagent to a predetermined point, and means for actuating said feeding means; the improvement wherein said actuating means comprises a tiltably mounted, fluid accumulating vessel adapted to be arranged adjacent a path of fluid flow for receiving a portion at 35 least of said flow, said vessel being closed and having a liquid receiving tray thereon for initially accumulating liquid supplied thereto, and adjustable inlet control means between said tray and the interior of said accumulating vessel for conveying liquid from said tray to the interior of the vessel, said control means being adjustable to determine the rate of flow into the vessel.

40 7. In a device of the class described having means for feeding a predetermined quantity of powdered reagent to a predetermined point, and means to actuate said feeding means; the improvement which comprises an actuating means 45 comprising a tiltable fluid accumulating vessel adapted to be placed adjacent a point in the fluid flow, said vessel being substantially completely enclosed to provide an interior chamber and having an adjustable inlet aperture in the top wall and an outlet aperture in a side wall thereof.

50 8. In a device of the class described, a tiltable liquid accumulating chamber, a hopper for a body of powdered material, means connected 55 with said tiltable chamber to feed a predetermined quantity of said powdered material, a control arm on said last named means, and powder agitating means in said body of powderous material and operatively connected with said control 60 means.

arm and moved by actuation thereof for agitating the powdered means to prevent lumping thereof, said agitating means comprising a plurality of generally parallel elongated members movable laterally through the powder, certain of said elongated members adjacent said feeding means being arranged closely together and others of said members located relatively remotely from said feeding means and being relatively substantially spaced.

10. 9. A tilting chamber for use in combination with means for feeding a predetermined quantity

of powdered reagent, said tilting chamber being adapted to be arranged adjacent the path of flow of a liquid to accumulate a portion at least of said liquid for tilting when a predetermined amount of liquid has been accumulated, said tilting chamber being substantially closed and having a fluid receiving tray thereon, adjustable inlet means between said tray and the interior of said vessel for controlling the rate of admission of liquid to the vessel, and an outlet aperture in the side wall of said vessel.

OTTO C. SCHLACK.
